UNITED STATES PATENT OFFICE

2,188,989

SNOW REMOVER

August F. Werner, Alpena, Mich.

Application December 27, 1938, Serial No. 247,963

1 Claim. (Cl. 37—5)

This invention aims to provide a novel structure adapted to be attached to the rear end of a truck, novel means being provided whereby snow will be automatically scooped from one side of the truck and conveyed into the truck, as the same proceeds along the street, the truck and the snow-cleaning instrumentalities advancing along a strip from which the snow has been removed during a former trip along the street.

Other objects will appear as the description proceeds.

In the accompanying drawings:

Figure 1 is a side elevation of the improved self-loading snow remover;

Figure 2 is a longitudinal sectional view through the self-loading snow remover;

Figure 3 is a plan view of the improved self-loading snow remover;

Figure 4 is a sectional view taken on the line 4—4 of Figure 3; and

Figure 5 is a sectional view taken on the line 5—5 of Figure 3.

The self-loading snow removing device comprises an elongated trough-shaped body 1, having oppositely disposed side rails 2, a transversely disposed axle 3 being mounted at the lower end of the body, wheels 4, provided with traction cleats 5, being journaled on the axle.

Fixed upon the axle 3 at the opposite ends thereof, and inwardly of the wheels 4, are sprockets 6 and 7. Mounted at the upper end of the body 1, and disposed slightly below the same, is a transverse shaft 8, provided with sprockets 9 and 10 at its opposite ends.

A sprocket chain 11 connects the sprockets 6 and 9, and a sprocket chain 12 connects the sprockets 7 and 10. Disposed transversely of the body 1, and mounted upon the sprocket chains 11 and 12, are conveyor blades 13, of any desired form.

Attaching bars 14 and 15 are pivoted to the side rails 2 of the body 1, and carry at their outer ends, resilient clamping fingers 16 and 17 which are adapted to grip the upper edge of the tail-gate 18 or rear end of a truck 21.

Supported at the rear or lower end of the body 1 is a combined scoop and guide trough 19, the forward end of said scoop being provided with a reinforced blade 20, extending laterally on the adjacent wheel upon which the device is supported. The blade 20 of the combined scoop and guide trough is located closely adjacent to the surface of the ground, and the bottom of the scoop is inclined upwardly and in an arcuate manner, transversely of the draft line, to a point

at the level of the lower end of the body 1. An upstanding guide flange 26 extends along the opposite sides of the scoop and across the back of it, whereby when the device is pulled along, the snow will be automatically fed into the guide trough and will be elevated to the lower end of the conveyor, where the blades 13 will carry the snow upwardly along the body 1, and dump the snow into the truck 21.

Supporting legs 22 and 23 are pivoted at their forward ends to the sides 2 of the body 1, and are provided with foldable braces 24 and 25 which are pivotally secured to the sides of the body 1 at places below the pivotal connection between the supporting legs and the sides of the body. The purpose of the legs 22—23 is to support the device, when the same is not attached to a truck, thereby preventing injury to the conveyor structure.

The form of the guide flange 26 is such as to direct the snow, as it enters the scoop 19, around to a position adjacent the lower end of the conveyor, where the conveyor will pick it up and carry it into the vehicle 21. The guide flange 26 will prevent the snow from packing or caking up on the wheels 4, since, as shown in Fig. 3, the flange extends inwardly of one wheel, the bottom of the trough 19 being arched to extend over the other wheel.

The machine is secured to the upper edge of the tail-gate 18 of a truck 21, and the truck is advanced along the street, and the ground wheels 4 will operate the conveyor. The snow is received in the scoop and guide trough 19 and is automatically loaded into the truck by way of the conveyor. After one strip of street has been cleaned, the truck may then be advanced in this cleaned portion of the street, and the laterally-extending scoop 19 will remove the snow adjacent to the cleaned portion, until the full width of the street has been cleaned.

Changes in structure may be resorted to without departure from the spirit of the invention, if within the purview of what is claimed.

Having thus described my invention what I claim as new and desire to secure by Letters Patent of the United States is:

In a machine for removing snow from a street, a strip at a time, a frame, ground-wheels mounted to turn on the rear portion of the frame, means for connecting the forward portion of the frame detachably to the rear end of a towing and snow-receiving vehicle, in an upwardly-inclined position directly in the wake of the vehicle, a vehicle-loading conveyor carried by the frame and discharging at the vehicle-connected end thereof,

means for operating the conveyor from the ground-wheels, a scoop attached to the rear end of the frame, one side of the scoop terminating inwardly of one ground-wheel, the opposite side of the scoop extending forwardly, outwardly of the other ground-wheel, the scoop including a bottom which has a backward and upward longitudinal slant outwardly of said other ground-wheel, and an upward transverse slant to the lower, rear end of the conveyor, the bottom of

the scoop including an arched portion extended over said other ground-wheel, and an upstanding guide flange attached to the bottom and extending from one side of the scoop to the other, the flange being backwardly-concaved to permit snow to pass readily to the rear of the arched portion, and to direct the snow, by an easily travelled, curved path, to the lower, rear end of the conveyor.

AUGUST F. WERNER. 10
